DESIGN FOR A SHADE-BOWL.

Specification for Design.

Patented Feb. 10, 1914.

Application filed November 20, 1913. Serial No. 802,164. Term of patent 7 years.

To all whom it may concern:

Be it known that I, RUSSELL D. A. THOMPSON, a citizen of the United States of America, and resident of Beaver, county of Beaver, State of Pennsylvania, have invented a certain new, original, and ornamental Design for a Shade-Bowl, of which the following is a specification.

Referring to the drawings, Figure 1 is a view half in elevation and half in vertical, central section showing the bowl in upright position. Fig. 2 is a bottom plan of the same.

The shade consists of a bowl 1 ornamented by a design in the form of a ribbon or sash 2 suspended at points 3 spaced by convenient intervals with a bow 4 at each point of sus-

pension, the ribbon between the points of suspension being looped or permitted to hang down in the curve naturally imparted to it by the action of gravity, the bowl being otherwise ornamented as to minor figures and details.

I claim:

The ornamental design for a shade bowl substantially as shown and described.

Signed by me at Beaver, county of Beaver, State of Pennsylvania this 14th day of November, 1913.
